UNITED STATES PATENT OFFICE

149,909

DESIGN FOR A SEWING KIT OR SIMILAR ARTICLE

Theodore Scarlet, New York, N. Y.

Application November 5, 1946, Serial No. 134,519

Term of patent 3½ years

(Cl. D3—19)

To all whom it may concern:

Be it known that I, Theodore Scarlet, a citizen of the United States of America, residing in New York city, county of Bronx, and State of New York, have invented a new, original, and ornamental Design for a Sewing Kit or Similar Article, of which the following is a specification, reference being had to the accompanying drawing, forming part thereof, wherein:

I claim:

The ornamental design for a sewing kit or similar article, substantially as shown.

THEODORE SCARLET.
